SEAL FOR CONTAINERS

Jesse E. Roach, New York, and Harry C. Lohman, Brooklyn, N. Y., assignors to Cold Pack Container, Inc., Edgewater, N. J., a corporation of New Jersey

Application April 23, 1937, Serial No. 138,507

3 Claims. (Cl. 229—5.5)

This invention relates to new and useful improvements in containers and seals therefor and while the construction may be employed for packing many commodities, it has been found 5 in actual practice to be particularly adapted to packing preserves and products of similar character.

It is one object of the invention to provide a new and improved container which is of relatively cheap manufacture and which may be used for packing a commercial product.

A further object of the invention is to provide a new and novel construction of container and seal and so to construct the seal that the same 15 may be placed in the container by automatic machinery.

A further object of the invention resides in the provision of a new and novel seal which will exclude air from the contents of the container to which it is applied.

With the above and other objects in view, reference is had to the accompanying drawing, in which;

Figure 1 is a perspective view of a sealing element constructed in accordance with the present invention,

Figure 2 is a bottom plan view on an enlarged scale,

Figure 3 is a transverse sectional view thereof on an enlarged scale taken substantially on the line 3—3 of Figure 2,

Figure 4 is a longitudinal sectional view of a container showing a seal constructed in accordance with the present invention in sealing position therein,

Figure 5 is a detail view showing a plurality of sealing elements in stacked relation, and;

Figure 6 is a detail fragmentary sectional view taken on an enlarged scale showing a detail of construction and its function.

Referring more particularly to the drawing, the seal consists of a disk-like member having a main body portion 10. Defining the peripheral edge of the main body portion 10 there is an annular flange 12 which is radially corrugated as at 13.

The main body portion 10 and the annular flange 12 are in spaced parallel planes and they are connected by an angularly disposed wall 14. This wall 14 provides the means for spacing the body portion 10 of the sealing member and the annular flange 12 thereof in separate planes.

The main body portion 10 of the disk-like member is provided with an annular internal bead 16 which extends completely around the

body portion closely adjacent the wall 14 and this bead provides a reinforcement for the main body portion of the disk-like member.

These sealing elements are adapted to be placed in containers such as 20 by automatic machinery and to facilitate this operation a plurality of the disk-like sealing members are arranged in stack relation, as illustrated in Figure 5.

In order to prevent close nesting of the sealing elements when stacked as illustrated in Figure 5, which condition would interfere with the proper feeding of the sealing elements by the automatic machinery, we provide a plurality of indentations 22. These indentations 22 are 15 spaced about the circumference of the disk-like member, which aids in preventing nesting thereof, since the projection on one member will rest upon the bead of the next lower member or, in other words, upon the member by which it is supported in the stack. It will be noted that this spacing alone will not suffice to prevent nesting, but nesting is further prevented by reason of the fact that the bottom wall of each of the indentations 22 is larger in its outside 20 dimensions than the inner dimension of said indentations and therefore, should two disks become positioned with respect to each other so that the indentations would register, the indentations could not pass one into the other by reason of the enlarged outer diameter thereof, as indicated at 28 in Figure 6. It is also to be noted that these indentations extend, as indicated at 30, through the angular wall which serves as the connection between the main body 30 portion and the annular flange, all of which tends to lend strength and rigidity to the sealing element.

In use, the sealing element is of a size or diameter to be received within the bead 40 formed in the side walls of the container 20, as illustrated in Figure 4. When in this position, the angular wall 14, the annular flange 12 and the adjacent side wall of the container form a channel 42 for the reception of a sealing medium 44, of which paraffin wax is one very good example, and when the parts have been assembled and the paraffin wax applied it will be apparent that an effective seal which not only holds the sealing element in place, but serves to prevent the ingress of air 45 to the container around the seal, is provided.

These sealing elements may also be employed to form the bottom of a container and when so employed the container may have an inwardly folded portion 46 which provides a shoulder 48 for the 50 55

reception of the annular flange 12 of the seal and the several parts function together to receive the sealing medium 44 as in the case where the sealing elements are used to close the container.

5 From the foregoing it will be apparent that the present invention provides a new and improved form of seal for containers which is so constructed that the sealing element will be securely held in place and an air tight seal provided.

10 It is to be understood that the invention is not limited to the construction herein shown but that it may be provided in other forms without departing from the spirit and scope of the appended claims.

15 Having thus described the invention, what is claimed as new, is:

1. A seal for containers comprising a disk-like member having its main body portion disposed in one plane, an annular flange defining the peripheral edge of said main body portion, said flange being disposed in a parallel, but different plane from that of the main body portion, an angularly disposed wall connecting the annular flange with the main body portion, a bead formed in said main body portion adjacent the angular wall, and a plurality of depressions formed at spaced intervals in said angular wall and extending into said bead.

20 2. A seal for containers comprising a disk-like member having its main body portion disposed in one plane, an annular flange defining the peripheral edge of said main body portion, and an angularly disposed wall connecting said flange with said body portion and maintaining said main body portion and said flange in spaced relation, said angularly disposed wall having a plurality of indentations therein arranged in spaced relation to one another.

25 intervals in the angular wall and extending into said bead.

3. A seal for containers comprising a disk-like member having its main body portion disposed in one plane, an annular flange defining the peripheral edge of said main body portion, said flange being disposed in a parallel, but different plane from that of the main body portion, an angularly disposed wall connecting the annular flange with the main body portion, a bead formed in said main body portion adjacent the angular wall, and a plurality of depressions formed at spaced intervals in said angular wall and extending into said bead.

3. A seal for containers comprising a disk-like member having its main body portion disposed in one plane, an annular flange defining the peripheral edge of said main body portion, and an angularly disposed wall connecting said flange with said body portion and maintaining said main body portion and said flange in spaced relation, said angularly disposed wall having a plurality of indentations therein arranged in spaced relation to one another.
